UNITED STATES PATENT OFFICE

CARL B. SCHEFFOLD, OF MARQUIS, SASKATCHEWAN, CANADA

ROAD GRADER ATTACHMENT

Application filed February 8, 1932. Serial No. 591,696.

This invention relates to a slope attachment for a conventional road grader.

It is an object of this invention to provide an attachment which enables sloping operations, such as grading, sloping or slanting banks at the sides of a road, to be carried out expeditiously and efficiently, simply by moving the grader forwardly with the attachment in engagement with the material of the bank or the like.

It is also an object of this invention to provide a slope attachment for a conventional road grader which enables accurate work of the character described to be done in conditions where the material of which the slope is composed is either wet, muddy or lumpy, in which condition the use of picks and shovels, and other means would be ineffective.

It is also an object of this invention to provide an attachment of the type described which does not involve alterations to the conventional road grader structure beyond the making of several bolt holes and other minor changes in parts of the grader and its existing blade.

Other objects and advantages of the invention will be apparent during the course of the following description.

In the accompanying drawings forming a part of this application and in which like numerals are employed to designate like parts throughout the same,

Figure 1 is a rear view of a conventional road grader showing the attachment of the invention installed in operative position.

Figure 2 is a view similar to Figure 1 slightly enlarged and showing the attachment of the invention in inoperative position.

Figure 3 is a top plan view.

Figure 4 is a side elevational view of a guide bracket mounting the attachment to the grader.

Figure 5 shows a shield used on the blade of the attachment.

Figure 6 shows a chain employed to support the attachment in inoperative position.

Figure 7 is a horizontal sectional view taken through the blade of the grader and the

blade of the attachment at the level of the guide bracket.

Figure 8 shows a group of parts associated with the guide bracket.

Figure 9 is a vertical sectional view of the anchorage of the cable and turn buckle structure shown in Figure 10 which forms the draft cable connection to the frame of the grader.

Figure 10 shows the turn buckle of the cable structure.

Figure 11 is a sectional elevational view of the adjustable rocker arm.

Figure 12 is a top plan view of Figure 11.

Figure 13 is a transverse vertical sectional view through the trip latch structure of the rocker arm taken through the left hand portion of Figure 11.

Figure 14 is a top plan view of a bracket mounted on the grader circle for mounting the inward end of the rocker arm.

Referring in detail to the drawings, the numeral 5 generally designates a conventional grader which has the conventional grader blade 6, provided with the usual horizontal angle iron brace 7 on the back thereof. Upon the outward end of this angle iron and attached by vertical bolts passed therethrough, I provide a guide bracket generally designated 8 which is of the form shown in Figure 4 providing a horizontal portion 9 through which the attaching bolts are passed, and the vertically enlarged portion 10 which extends outwardly over the end of the angle iron brace 7, and which is provided with the transversely elongated guide slot 11. This guide bracket 8 pivotally and slidably receives a pivot member 12 to be described.

Another bracket shown in Figure 14 and designated 13 consists of a vertically disposed plate 14 attachable to the side of an upper portion of the grader blade circle, has a pair of parallelly spaced vertical, laterally projecting arms 15, 16, which are transversely bored to receive the pivot 17 carrying the inward end of the rocker arm as seen in Figure 11. The bracket 13 is mounted on the upper portion of the grader blade supporting circle 18 of the grader as shown in Figure 3.

As seen in the drawings the slope blade

of the attachment of my invention consists of a conventional blade construction of elongated generally rectangular form which is provided at its inward end with an inverted triangular formation 19 to the back of which is attached an upwardly projecting standard 20, the standard 20, and the blade itself being pierced and the two of them secured together by bolts. In the drawings the blade of the attachment is generally designated 21. From a point near the upper end of the standard 20 and angularly and downwardly directed brace 22 extends to a point 23 near the outward end of the back of the blade 21. The space between the brace 22 and the upper edge of the blade 21 is covered by a shield 24 held by cleats 25 seen in detail in Figure 2. At the inward extremity of the triangular portion 19 there is attached a short chain 26 having a hook 27 for engaging over the upper edge of the grader blade 6 so as to prevent over tilting of the attachment when it is brought into inoperative position. This is illustrated also in Figure 2.

25 Of course, it is understood that the blade 21 is attached at the end portion of the blade 6 in co-extensive overlapping manner. The means of connection to the blade 6 takes the form of the pivot member 12 passed through the end portion of the blade 6 through the blade 21, through the standard 20, then through the slot 11 in the bracket 8, the portion 10 of the bracket being spaced from blade 6. On the pivot member 12 is a sleeve 28 which takes the vertical play from this arrangement in the slot 11, and on the rearward end of the pivot member 12 is secured a collar 29 locked on the pivot member by means of a transverse bolt 30 passing through a bore 31 in the rearward end of the pivot member 12.

40 For raising and lowering the attachment of the invention there is provided a rocker arm generally designated 32 which may consist of a tubular shaft 33 provided at its outer end with a thickened portion 34 which is internally screw-threaded as indicated at 35 to receive a screw-threaded shank 36 which has at its outward end a swivel member 37 one section 38 of which is connected to the upper end of the standard 20, the member 38 being of clevis formation, and is so secured by means of a pivot 39 passing through the upper end of the standard 20. An oiler, such as a grease cup or the like 40 is provided to extend through the side of the tubular member 33 in the position shown in Figure 11. The inward end portion of the tubular member 33 is equipped with a U-shaped casing 40 whose disposition is shown in Figure 13, and which is secured by means of a transverse bolt 41 to the said end portion, which permits it to swing away therefrom. The end of the casing 40 opposite the attachment bolt 41 is adapted to merge into a block 42 which has parallel arms extended therefrom as indi-

cated at 43 for engagement on the bracket 13, and the outward end of the block 42 is step cut to receive the extremity of the tubular member 33 as shown in Figure 11. The casing 40 has a screw-threadedly adjustable stop 43 and a cam member 44 operable by a lever 45 for lifting the tubular member 33 away from the casing 40 so as to break the joint in the manner illustrated in Figure 2. A spring 46 extended between the lever 45 and the block 42 retains the lever normally in operative position when the joint is closed. Inspection of Figure 2 will disclose the motion or movement of the rocker arm structure which brings the blade of the attachment from the operative to inoperative position, and Figure 1 illustrates the operative position of the blade of the attachment as the result of closing the joint in the rocker arm. For adjusting the operative angularity of the attachment, the threaded shaft 36 is to be rotated by engaging the member 37 with a rotating means so as to extend or retract the member 36 from the tubular member 33. The bracket 13 carries a chain 47 which has a clevis 48 at one end for attaching it to the bracket 13 and a hook 49 at the other end for engaging in a hole in the flange of the member 37 as shown in Figure 2 so as to maintain the inoperative position of the attachment.

50 The draft cable 50 shown particularly well in Figure 3 is attached to a bracket 51 at the forward part of the grader frame and to an eye 52 secured to project from the forward side of the attachment blade 21 shown in detail in Figure 9 and Figure 10. Figure 10 reveals the provision of a turn buckle 53 for properly tightening the draw cable 50. As shown in Figure 3, the blade of the grader and consequently the blade of the attachment will not be disposed in operative position at a right angle laterally of the grader, but will have a slightly backward deviation.

55 In operation, the attachment being in place and adjusted to the desired vertical angularity, the grader is moved forwardly as in ordinary grading work, and close to the side of the road desired to be banked or sloped, and the result will be a smooth perfectly formed slope, the operation being accomplished either simultaneously with grading the road-bed or as a separate operation, in either case saving a great deal in labor and making possible a more efficient and satisfactory slope or bank. It will be observed that the slight relative movement of the blade of the attachment with the blade of the grader is taken care of by the elongation of the slot 11 in the guide bracket. Of course, the operation of the lever 45 so as to break the joint will enable the movement of the attachment out of the operative position shown in Figure 1 to the inoperative position shown in Figure 2 whereupon the chain 47 is engaged with the rocker arm to maintain the position of the

attachment. This will bring the attachment safely out of operative position and permit movement of the grader as desired when meeting obstacles or when it is desired to suspend operation of the device or attachment. The construction is such as to provide adequate strength and mechanical efficiency.

It is to be understood that the form of my invention herewith shown and described is to be taken as a preferred embodiment of the same, and that various changes in the shape, size and arrangement of parts may be resorted to, without departing from the spirit of my invention or the scope of the subjoined claims.

What is claimed is:—

1. An attachment for a road grader comprising, in combination, a conventional road grader having a "circle" carrying a road surfacing blade, a sloping blade mounted to extend from the outward end of the grader blade, adjustable means connected between the inward end portion of the sloping blade and the "circle" of the grader for supporting the sloping blade at a desired adjusted angle with the horizontal, and a draft means connected between the outer end portion of the sloping blade and a forepart of the grader.

2. An attachment for a road grader comprising, in combination, a conventional road grader having a "circle" carrying a road surfacing blade, a sloping blade mounted to extend from the outward end of the grader blade, adjustable means connected between the inward portion of the sloping blade and the "circle" of the grader for supporting the sloping blade at a desired adjusted angle with the horizontal, and a draft means connected between the outer end portion of the sloping blade and a forepart of the grader, said adjustable means consisting of a longitudinally adjustable arm having a hinged joint therein, and means thereon to break the joint so as to swing the sloping blade out of ground engaging position.

3. An attachment for a road grader comprising, in combination, a conventional road grader having a "circle" carrying a road surfacing blade, a sloping blade mounted to extend in longitudinal alignment from the outward end of the grader blade, adjustable extensible means connected between the inward end of the sloping blade and the "circle" of the grader for supporting the sloping blade at a desired adjusted angle with the horizontal, and a draft means connected between the outer end of the sloping blade and a forepart of the grader, said adjustable extensible means consisting of a longitudinally adjustable arm having a hinged joint therein, and means thereon to break the joint so as to swing the sloping blade out of ground engaging position, said sloping blade

being pivotally mounted on the outward end portion of the grader blade.

4. A road grader comprising a grader structure including grader blade supporting circle and grader blade carried thereby, a slope forming blade pivotally mounted on one end of the grader blade, draft means connected between the outer end portion of the slope forming blade and a forward part of the grader, and means for adjusting and maintaining the angularity of the slope forming blade with respect to the grader and for withdrawing the slope forming blade out of ground engagement comprising a longitudinally adjustable arm having a lockable break joint, the arm being pivotally connected to the grader blade supporting circle and to the inward end portion of the slope forming blade, and bracket means on the inward end portion of the slope forming blade rising above the upper edge thereof to which said arm is connected.

In testimony whereof I affix my signature.

CARL B. SCHEFFOLD.
